UNITED STATES PATENT OFFICE.

LEONHARD HORN, OF AUGSBURG, GERMANY, ASSIGNOR TO MASCHINENFABRIK AUGSBURG-NUERNBERG, AKTIENGESELLSCHAFT, OF AUGSBURG, GERMANY, A CORPORATION OF GERMANY.

STARTING AND STOPPING DEVICE FOR OFFSET-PRINTING MACHINES.

Application filed July 22, 1925, Serial No. 45,184, and in Germany September 1, 1924.

My invention relates to a device for rendering operative and inoperative the cylinders and inking rollers of rotary offset-printing machines and consists more essentially 5 in providing an appliance for each printing machine, whereby the cylinders and inking rollers may be moved into and out of operative positions the actuating members being electrically connected with each other 10 in such a manner, that they may be operated either simultaneously, individually or in groups.

Further objects of my invention are to provide means for individually operating 15 the several appliances, which are associated with the printing machines, by the latter, so as to have each appliance connected with its corresponding printing machine by an electric coupling also, to provide means for 20 securing the appliances in their temporary positions, and finally to so arrange the terminals of the windings of the coupling magnets for the several printing machines, that each winding may be individually 25 connected.

The known devices for rendering operative and inoperative the cylinders and inking rollers of rotary printing machines for offset-printing, especially in rubber printing machines having several printing mechanisms for printing in a plurality of colors, consist essentially in a rocking double pawl which imparts a definite angular motion to a segment and the various parts connected therewith. This construction has the disadvantage that the desired action does not take place at once, but only after the pawl has come into a certain angular position. In that way, especially in case of auxiliary 35 motors, that is to say, in case of slow operation of the machine, a great loss of time is caused. To be sure, devices are known, whereby said disadvantage may be avoided, but in these devices, a special electric motor is necessary for the operation. The two just referred to constructions have still a further disadvantage. In all known devices of this kind, the motion producing the operative and inoperative position of the machine originates from a machine element, from which the angular motion necessary for producing the inoperative position is conveyed to the cylinders and rollers to be moved to inoperative position. Since the

cylinders and rollers as a rule are positioned 55 at a great distance from each other, there are required complicated rod systems, which are liable to cause difficulties in connection with the mounting and assembling of the parts and in connection with the operation; 60 in addition thereto, such complicated rod systems render the machine in a considerable degree less accessible. The device for producing the inoperative position becomes still 65 more complicated, if the necessity arises of throwing several printing machines into inoperative position, as is the case with most machines of this kind, especially machines for multi-color printing. Coupling devices must therefore be provided, which are included in the rod systems, in order to enable the devices for the several printing machines to be coupled and uncoupled.

All these disadvantages are avoided by the present invention, which is based upon 75 the principle, that each printing machine shall be provided with an individual device for producing the operative and inoperative position, which device is operated 80 by the corresponding printing machine. The device itself, according to this invention, is located in immediate proximity to the parts to be controlled, so that the above 85 said rod system, which is of a complicated nature and liable to obstruct the access to 90 the machine, can be dispensed with. The devices according to this invention are operated by electrically controlled couplings, which are manually connected in the circuit by means of a push button, and which 95 are automatically disconnected by means of a second push-button. By such an arrangement it will be possible to start and stop the printing machines either individually, or simultaneously, or in groups, as desired.

In the drawings in which I have, by way of illustration shown an embodiment of my invention, Fig. 1 is a side elevation of a printing machine provided with the mechanism for producing the inoperative position; Fig. 2 is a section along line A—B—C in Fig. 1 and Fig. 3 a diagram representing the electrical connections of the couplings for several printing machines.

The printing machine shown in Fig. 1 105 comprises the plate cylinder *a*, the rubber cylinder *b* and the impression cylinder *c*. The mechanism for rendering inoperative

the rubber cylinder *b* and the inking rollers *d* is operated from the shaft *e* which is rotated from the shaft *i* of the rubber cylinder *b* by means of the gears *f*, *g*, and *h*. The shaft *e* carries an eccentric *k* which operates a lever. The shaft *i* being eccentrically mounted and its bearing being rotated by action of the eccentric *k*, the shaft *i* and the rubber cylinder *b* will receive a rocking motion.

For rendering inoperative the inking rollers *d*, the double lever *m* is used which is mounted to rock about shaft *t*, said double lever being likewise actuated by the lever of the eccentric *k* and more particularly by the aid of a connecting rod.

The mode of coupling the shaft *e* with the cylinder shaft *i* will be seen in Fig. 2. Three electro-magnets *o* are mounted upon a common supporting plate *p*. Said magnets, when energized by an electric current, will attract their armatures *r* which are mounted upon a common plate *q*. Thereby, the gear *f* which is longitudinally displaceable upon the shaft *i* and mounted upon the plate *q* will be connected with the cylinder shaft *i* by means of the clutch *s*. The shaft *e* will now be rotated by the gear *g*, which meshes, on the one hand, with the gear *f* and, on the other hand, with the gear *h* secured to shaft *e*. On the latter there is furthermore mounted a cam-disc *u*, having in its circumference two depressions displaced from each other by 180° , and adapted to receive the spring-actuated roller *t* to thereby secure the several parts in their positions. Furthermore two projections *v* are provided upon the gear *h*, said projections in their end positions pressing the push-button *w*, thereby interrupting the electric current for said magnets. The coupling *s* is controlled by the action of springs *x* designed to disengage said coupling, as soon as the current for the magnets is interrupted.

Fig. 3 shows the connections for the coupling magnets *O¹*, *O²* and *O³*, of three printing machines I, II and III, respectively, said printing machines being operated by pressing the push-buttons *n¹*, *n²* and *n³*. By means of the projections *v¹*, *v²* and *v³*, the conduit for the connections to the coupling magnets *O¹*, *O²* and *O³* will be interrupted. The two terminals of the magnet windings are connected with each other by way of the disconnecting switches *y¹*, *y²* and *y³*, in such a way that every winding may be individually disconnected.

The mode of operation will now be briefly described. If it is desired to throw out of operation the printing machine shown in Fig. 1, the corresponding push-button, such as for instance the push-button *n¹*, which had so far been interrupted at the point *w*, will be supplied with current. The magnet *o* consequently will attract its armatures *r*,

and the gear *f* will be connected with the cylinder shaft *i* by means of the clutch *s*. The controlling shaft *e* being rotated from the cylinder shaft *i*, the eccentric *k* will rotate through 180° about the shaft *e*, until the roller *t* will enter the respective depression of the cam-disc *u*. The lever of the eccentric *k* will rotate the bearing, and the rubber cylinder *b* will be rocked by reason of the eccentric mounting of the cylinder shaft *i* about the central axis of said bearing and will thereby be disconnected from the plate cylinder *a*. When the cylinder *b* has reached its inoperative position, it will be locked in said position by means of the roller *t*. At the same time the projection *v* will press the push-button *w*. The current for the magnets will thus be interrupted and the coupling *s* be disengaged by means of the spring *x* so that the eccentric *k* will remain in a position of rest. By a further pressing of the push-button, a rotation of 180° will again be imparted to the eccentric *k* and the rubber cylinder *b* will again be moved to operative position, while the circuit for the magnets during the position of rest of shaft *e*, as shown in Figs. 1 and 3, will remain interrupted, the cam *v* having raised the contact clip.

If the three switches *y¹*, *y²* and *y³*, are opened, the printing machines I, II and III may be rendered inoperative individually, according as to whether the push-button *n¹*, *n²* or *n³* is depressed. If all the switches are closed, a pressing of one of said three push-buttons will cause all the magnets to respond, and consequently all the printing machines will be thrown out of operation. If only two of the switches are closed, only the corresponding printing machines will be rendered inoperative. The closing of the switches *y¹* and *y²* for instance, will cause only the printing machines I and II to be rendered inoperative. In the arrangement as described, the printing machines may, therefore, be rendered inoperative either individually, in groups, or as a whole.

I claim:

1. A device for rendering operative and inoperative the cylinders and inking rollers of rotary off-set printing machines having a plurality of printing units, comprising an actuator associated with each of said printing units and adapted to move into and out of operative position the cylinder and inking rollers of said unit, an electric circuit including the various actuators, and means enabling said actuators to be operated either simultaneously, individually or in groups.

2. A device for rendering operative and inoperative the cylinders and inking rollers of rotary offset printing machines having a plurality of printing units, comprising an actuator provided for each of said printing units and adapted to move into and out of

- operative position the cylinders and inking rollers of said unit, an electric circuit including the actuators of said units, and manually operated means enabling said actuators to be operated either simultaneously, individually or in groups.
3. A device as specified in claim 2, comprising an electrically operated coupling connected in said electric circuit, and means 10 associated with said actuator for automatically causing said coupling to be disconnected.
4. A device for rendering operative and inoperative the cylinders and inking rollers 15 of rotary offset printing machines having a plurality of printing units comprising a rotatable shaft, an eccentric mounted thereon for each of said printing units, operative connections between said eccentric and the 20 cylinder and inking rollers of each unit, means for rotating said shaft, an electric circuit including said means, a switch for connecting and disconnecting said means at will, and a means for automatically disconnecting said means at predetermined intervals.
- 25 5. A device as specified in claim 4, comprising a notched disc associated with said eccentric, and a spring controlled roller adapted to enter the notches in said disc 30 for temporarily securing the various parts in their positions.
6. A device for rendering operative and inoperative the cylinders and inking rollers 35 of rotary offset printing machines having a plurality of printing units, comprising a rotatable shaft, means associated with each of said printing units controlled by said shaft for moving into and out of operative position the cylinder and inking rollers of each 40 of said units, means for rotating said shaft, a coupling between said shaft and said rotating means, an electric circuit, electro magnets in said circuit for operating said coupling, and manually operated means for 45 opening and closing said circuit.
7. A device as specified in claim 6, comprising means controlled by said rotatable shaft for automatically connecting and disconnecting the means for moving said cylinders and inking rollers into and out of operative position.
- In testimony whereof I have affixed my signature.

LEONHARD HORN.
